UNITED STATES PATENT OFFICE.

CLARENCE L. FINCH, OF ROCHESTER, NEW YORK, ASSIGNOR TO THE PFAUDLER COMPANY, OF ROCHESTER, NEW YORK, A CORPORATION OF NEW YORK.

FLANGING MACHINE.

No. 914,034.

Specification of Letters Patent.

Patented March 2, 1909.

Application filed September 18, 1907. Serial No. 392,627.

To all whom it may concern:

Be it known that I, CLARENCE L. FINCH, of the city of Rochester, county of Monroe, and State of New York, have invented certain new and useful Improvements in Flanging-Machines; and I do hereby declare the following to be a full, clear, and exact description of the same, reference being had to the accompanying drawings, forming a part of the specification, and to the reference-numerals marked thereon.

The present invention, which relates to machines for flanging metallic bands, pipes, tank sections or other open ended hollow bodies, has for an object to provide a construction which will cost less to manufacture and will reduce the time required for flanging the two ends of a hollow body, thus providing an increased output for the machine.

Another object is to provide a construction by which the hand trimming of the flanges is obviated.

To these and other ends the invention consists in certain improvements and combinations of parts all as will be hereinafter more fully described, the novel features being pointed out in the claims at the end of the specification.

In the drawings: Figure 1 represents a front elevation of a machine constructed in accordance with my invention. Fig. 2 represents a side elevation with one of the bending devices shown in vertical section. Fig. 3 shows a horizontal section of the chuck or holder, the cutting, bending and supporting devices being shown in plan before the flange is formed. Fig. 4 is a detail view showing the position of the parts after bending. Fig. 5 is a detail view showing the operative position of another form of cutting device, and Fig. 6 shows the machine arranged to cut smaller bands.

In the production of flanges on bands of large diameter such as those used in the construction of beer vats it is customary to hold or support the section or band in such a manner that not only are very heavy and consequently expensive parts required but it is impossible to produce over one flange at each operation, and, as these operations are very slow, the cost of making a section flanged at both ends is very great. By a machine constructed in accordance with this invention the ring is supported interiorly, thus making it possible to reduce the weight and conse-

quently the cost of the machine, and at the same time to form a flange at both ends simultaneously.

In the embodiment of the invention herein shown there is employed a bed plate 1 on which preferably is arranged supports 2 on the upper portions of which is journaled a shaft or spindle 3 which carries the chuck or rotary holder. The chuck is formed preferably by arranging at one end of the shaft 3 a head 4, the outer face of which preferably has a plurality of jaws 5 movable thereon, being for this purpose formed with radial guides 6 on which move slides 7 to which the jaws 5 are secured by bolts 8, permitting their removal and the attachment of other jaws 5 of different length. All of the jaws have their outer faces curved near both edges at 5° so that when the chuck is expanded they will lie flush against the inner surface of the band. The expansion of the jaws is effected by any suitable means, but it is preferred to connect them by links 9 to a plunger 10, the links being united to the plunger by two disks 11 and 12 arranged between a flange 13 and a nut 14 on the plunger and receiving pivots 15 integral with the links. The plunger is mounted in the shaft 3 which for this purpose is made hollow, while to the outer end of the shaft is secured a fluid pressure cylinder 16 which rotates with the shaft and has its piston 17 connected to the plunger 10.

In order to rotate the chuck or holder, it is preferred to employ an internal gear 18 integral with the inner face of the head 4 and having a drive shaft 19 geared thereto by a pinion 20, said shaft 19 being also journaled on the supports 2.

Arranged to operate on the projecting edges of a band positioned on the chuck are the bending devices which in this instance are in the form of rollers 21 each mounted so as to swing about an axis coincident with a portion of a peripheral edge of the chuck, and adjustable in a direction parallel to the turning axis of the chuck and also in a direction transverse to said axis. For this purpose I may provide the bed 1 with grooves or guides 22 in which work bolts 23 carried by supports 24 on each of which a carrier 25 is guided to be driven by a motor shaft 26 journaled in the support or by a manually operable shaft 27 journaled in the carrier, this double adjustment of the carrier being accomplished by 110

a worm wheel 28 with which a worm on shaft 27 meshes, and which has a screw threaded connection with shaft 26 so that the rotation of either shaft will effect the adjustment of 5 the carrier. Movable on a carrier 25 in a direction parallel to the axis of the chuck is a carrier 29 the adjustment of which is effected by a motor shaft 30 and a manually operable shaft 31 by means of a worm wheel 32 mounted in a manner similar to the worm 28. This 10 carrier 29 is provided on one of its sides with a semicircular or arcuate guide 33 on which travels the bender carrier 34, the adjustment of the latter being effected by a worm shaft 35 meshing with a curved rack 36, on the carrier 34. The bender device 21 is journaled on said carrier 34 so as to engage a projecting portion of a band on the chuck. In order to 15 support those portions of the band in proximity to the bending devices, I employ supporting devices preferably in the form of rollers 39 in this instance, secured to opposite ends of a shaft journaled on a carrier 40 which is adjustable on a support 41 toward 20 and from the chuck after each operation by means of screw shaft 42, or other means, the support 41 being also adjustable on bed plate 1 in order to obtain a coarse or rough adjustment by bolts 43 or other means.

25 30 Mounted on that side of the chuck opposite the bending devices so as to operate in a direction parallel to the axis of the chuck, are the cutting devices, one for the flange at each end of a band. These cutting devices in the preferred form are mounted on a support 44 roughly adjustable to and from the chuck on the bed plate for different sizes of bands by 35 bolts 45, or other means, and having a carrier 46 adjustable also to and from the chuck after each bending operation by a screw shaft 47. On this carrier is arranged the cutting device which may consist of two arms 48 pivoted together at 49 and at their free ends carrying roller cutters 50 which are forced 40 together gradually to cut from opposite sides of a flange by means of a yoke or link 51 having a set screw 52. Another embodiment of 45 the cutting device is shown in Fig. 5, wherein one of the arms 48^a is longer than the other, while the roller cutter 50^a is a flat roller and the cutter 50^b has a knife edge and is mounted on the shorter arm and bears on the flange at one edge of the roller 50^a.

50 55 In operation, the chuck is provided with jaws which when in clamping position will exactly fit the inner wall of the band to be flanged. Upon the surrounding of the chuck by the band, the jaws are moved outwardly by means of fluid admitted under pressure 60 into the cylinder through a flexible piping 38, or other device, which permits the rotation of the cylinder. At the end of the movement of the jaws the links have their inner ends positioned further inward than their outer 65 ends, and as a consequence a locking of the

jaws takes place, the fluid in the cylinder preventing their unlocking due to jars or other causes. As a further means for holding the jaws against movement, the proximate edges of the jaws are interlocked as by 70 clamping plates 40 secured to head 4 by bolts 41. The rollers 21 are now adjusted so that their peripheries are in a plane with a portion of the periphery of the chuck and engage the inner face of the band, as shown in 75 Fig. 3, and the supporting devices are adjusted to bear on the band with their outer edges located at the points where the flanges proceed from the band. Upon the rotation of the chuck the rollers 21 are turned gradually by means of the shaft 35 and the supporting devices 39 bear upon the band in 80 proximity thereto to prevent undesirable bending. After the band is completed or during the last portion of the bending operation, the cutting devices are engaged with the flange and flanges of equal width are thus 85 secured.

90 Of course, when the jaws 5^a are of less length than the head 4 as in Fig. 6, it is 90 possible to form flanges at only one end of a band. In both embodiments during the removal and the fitting of a band, it is unnecessary to move the supports of the several devices on the bed plate 1, as these devices 95 may be moved away from the chuck by moving the carriers on the supports.

95 From the foregoing it will be noted that I have provided a machine by which the manufacture of flanged open ended hollow 100 bodies may be accomplished in a very short time and that the flanges produced therefrom are trimmed to a uniform width.

I claim as my invention:

1. In a flanging machine, the combination 105 with a rotary chuck or holder having gripping jaws movable outwardly thereon to engage the interior of the band and formed to support the latter internally in proximity to that portion that is to be bent to form the flange, 110 of a flange bending device mounted to operate on an edge of the band on the chuck, and a supporting device to engage the band on its exterior in proximity to the bending device.

115 2. In a flanging machine, the combination 115 with a chuck or holder having gripping jaws movable outwardly thereon to engage the interior of the band and formed to support the latter internally in proximity to that portion that is to be bent to form the flange, 120 of a flange bending device mounted to operate on an edge of the band on the chuck, and a roller to engage the band on its exterior in proximity to the bending device.

125 3. In a flanging machine, the combination 125 with a rotary chuck or holder having gripping jaws movable outwardly thereon to engage the interior of the band and formed to support the latter internally in proximity to that portion that is to be bent to form the 130

flange and a flange bending device mounted to operate on an edge of the band on the chuck, of a device mounted independently of the chuck for supporting the band in proximity to the bending device.

4. In a flanging machine, the combination with a rotary chuck or holder having gripping jaws movable outwardly thereon to engage the interior of the band and formed to support the latter internally in proximity to that portion that is to be bent to form the flange and a flange bending device mounted to operate on an edge of a band on the chuck, of a roller supported independently of the chuck in a position to bear on the band in proximity to the bending device.

5. In a flanging machine, the combination with a rotary chuck or holder having gripping jaws movable outwardly thereon to engage the interior of the band and formed to support the latter internally in proximity to that portion that is to be bent to form the flange, of flange bending devices mounted to operate on opposite edges of the band on the chuck, and devices supporting the exterior of the band in proximity to the bending devices, said devices being mounted independently of the rotary chuck.

6. In a flanging machine, the combination with an expansible chuck having jaws provided with outer curved gripping faces, of a pair of flange bending devices one arranged at each end of the chuck, and devices traveling on the outer face of a band on the chuck to support the band, in proximity to the bending devices.

7. The combination with a hollow shaft, of a head arranged on one end thereof and having radial guides, jaws guided radially on the head, and a plunger movable in said shaft and connected to the jaws.

8. The combination with a rotary chuck having movable jaws, of a fluid pressure cylinder having a piston movable therein and connected to the jaws.

9. The combination with a rotary chuck having movable jaws, of a plunger connected to the jaws, and a fluid pressure cylinder rotatable with the chuck and having its piston connected to the plunger.

10. The combination with a hollow shaft, of a head arranged at one end of the shaft, jaws movable on the head, a plunger movable in the shaft and connected to the jaws, and a fluid pressure cylinder turning with the shaft and having its piston connected to the plunger.

11. The combination with a hollow shaft, of a head arranged thereon, jaws guided radially thereon, a plunger movable in the shaft, and links connecting the plunger and the jaws.

12. The combination with a hollow shaft, of a fluid pressure cylinder secured to one end of the shaft and having a piston movable

therein, a plunger secured to the piston in the cylinder, a head arranged on the opposite end of the shaft, jaws guided radially on the head, and links connecting the plunger and the jaws.

13. In a flanging machine, the combination with a rotary chuck or holder having gripping jaws moving outwardly thereon to engage the interior of the band and to support the latter internally in proximity to that portion which is to be bent to form the flange, of a flange bending device adapted to bend a flange on a band supported on the chuck, a supporting device for bearing against the band in proximity to the bending device, and means permitting the adjustment of the supporting device toward and from the chuck.

14. In a flanging machine, the combination with a bed, of a rotary chuck or holder having gripping jaws movable outwardly thereon to engage the interior of the band and to support the latter internally in proximity to that portion which is to be bent to form the flange, a flange bending device for operating on a band supported on the chuck, adjustable on the bed in a direction parallel to the axis of the chuck and also transversely thereto, and a support adapted to bear on a band on the chuck in proximity to the bending device and adjustable on the bed transversely to the axis of the bending device.

15. In a flanging machine, the combination with a rotary chuck or holder having gripping jaws movable outwardly thereon to engage the interior of the band and to support the latter internally in proximity to that portion which is to be bent to form the flange, of a swinging roller mounted to travel over a band on the chuck in the plane of one of the edges of the chuck, and a roller mounted to bear on a projecting portion of a band in proximity to the first mentioned roller.

16. In a flanging machine, the combination with a rotary holder, of a carrier provided with a curved guide, a worm mounted to turn thereon, a bender carrier mounted on the curved guide of the first named carrier and having a curved rack thereon substantially in the middle of the guide with which the worm meshes, and a roller bender for operating on a band on the holder, journaled on the bender carrier and having its axis located in a plane with the curved guide.

17. In a flanging machine, the combination with a rotary holder, of a support arranged in proximity to the holder, a carrier guided on the support, a pair of shafts each adapted to adjust the carrier on the support, a second carrier guided on the first named carrier transversely to the guides of the latter, a pair of shafts each adapted to adjust the second named carrier on the first named

carrier, a bender carrier guided to turn on the second named carrier, and a bender mounted on the bender carrier to operate on the band on the rotary holder.

5 18. In a flanging machine, the combination with a rotary holder and a bed plate, of a support adjustable on the bed plate, a carrier guided on the support, a pair of shafts each adapted to adjust the carrier 10 on the support, a second carrier guided on the first named carrier, a pair of shafts each adapted to adjust the second named carrier on the first named carrier, a bender carrier guided to turn on the second named 15 carrier, and a bending roller mounted on the bender carrier to operate on a band on the rotary holder.

19. In a flanging machine, the combination with a rotary chuck or holder having 20 gripping jaws movable outwardly thereon to engage the interior of the band and to support the latter internally in proximity to that portion which is to be bent to form the flange, and a bed plate, of a flange 25 bending device to operate on a band on the chuck, a support adjustable toward and from the holder, a carrier guided on the support toward and from the chuck, and a roller journaled on the carrier to bear on 30 the band in proximity to the bending device.

20. In a flanging machine, the combina-

tion with a rotary chuck or holder having gripping jaws movable outwardly thereon to engage the interior of the band and to support the latter internally in proximity 35 to that portion which is to be bent to form the flange, of a pair of flange bending devices arranged to operate on opposite edges of the band, a support, a carrier guided on the support toward and from the 40 band, and a pair of rollers on the carrier arranged to bear on the band in proximity to the bending devices.

21. In a flanging machine, the combination with a rotary holder for a band and a 45 bending device arranged to form an outwardly extending flange on a band on the holder, of a cutting device mounted to trim the flange produced by the flange bending device.

22. In a flanging machine, the combination with a rotary holder for a band, and a flange bending device, arranged to form a flange on a band on the holder, and adjustable toward and from the axis of the holder, 55 and a cutting device adjustable toward and from the holder and arranged to trim the flange produced by the bending device.

CLARENCE L. FINCH.
